Fig. 2

Fig. 4

FIG. 1 is a front perspective view of a carousel advertising sign display for stores embodying my new design;

FIG. 2 is a side elevational view thereof, viewed from the left side of FIG. 1;

FIG. 3 is a side elevation thereof, viewed from the right side of FIG. 1;

FIG. 4 is a fragmentary rear elevational view thereof, the horizontal sign support being broken away for convenience of illustration;

FIG. 5 is a bottom plan view thereof;

FIG. 6 is a perspective view of a second embodiment of my new design;

FIGS. 7 and 8 are respectively end elevational views thereof as seen from the right and left ends of FIG. 6;

FIG. 9 is a bottom plan view thereof; and

FIG. 10 is a rear elevational view thereof.

The uprights in FIG. 1 are broken away to indicate indeterminate length and fragmentarily shown in FIGS. 2, 3, 4, 6, 7, 8 and 9 for convenience of illustration.

I claim:

The ornamental design for a carousel advertising sign display for stores, substantially as shown and described.
